Michael T. Kilgore*

UNITED STATES PATENT OFFICE

HUGH M. MCCLURE, OF KEARNEY, NEBRASKA

TOBACCO PIPE

Application filed September 16, 1931. Serial No. 563,041.

My invention relates to tobacco pipes and has for its object to provide an extremely simple and highly efficient tubular strainer of novel construction that is adjustable in diameter and preferably also in length so that it can be used in pipes having stem passages of different lengths and diameter. This improved tubular stem also involves not only the above but other important novel features, as will hereinafter fully appear in connection with the description of the drawings, which illustrate the preferred form of the invention applied in a pipe.

The general purpose of tubular strainers in smoking pipes is well-known and generally stated, is to intercept the heavy tobacco juices and prevent the same from being drawn into the mouth of the smoker. My improved tubular strainer accomplishes this general result and other desirable actions, certain of which have been above noted and others of which will presently appear.

In the accompanying drawing, which illustrates the invention, like characters indicate like parts throughout the several views.

Referring to the drawing:

Fig. 1 shows an ordinary tobacco pipe in axial section with one of my improved tubular strainers applied therein;

Fig. 2 is an enlarged section taken on the line 2—2 of Fig. 1;

Fig. 3 is a fragmentary section taken on the line 3—3 of Fig. 1;

Fig. 4 is a transverse section taken on the line 4—4 of Fig. 1;

Fig. 5 is a perspective view showing the improved tubular strainer turned upside down in respect to the position that it occupies in the pipe shown in Fig. 1;

Fig. 6 is a plan view of the inner end of the strainer tube; and

Fig. 7 is a perspective of that portion of the strainer that is shown in detail in Fig. 6, illustrating a slight modification.

The numeral 6 indicates the pipe bowl having the ordinary stem 7 connected to the tubular mouth piece 8 by a telescopic joint 9.

The tubular strainer is slit or split throughout a sufficient portion of its length to make the same radially expansible and contractible

and preferably, and as shown, it is split from end to end. This tubular strainer is preferably made from thin sheet metal bent to the form, best shown, and having considerable resilience so that it may be sprung or contracted to decreasing diameter and hence inserted into the aligned axial passages of a pipe mouth piece stem and bowl. In practice, the tubular strainer will be made of such great normal diameter that it will be large enough for pipes having what is assumed to be the maximum size of air passage and such being the case, it can, of course, be sprung into and made to fit pipes having smaller passages. Of course, the said split or slit tubular strainer is diametrically expansible as well as contractible. The inner end of the split tube 10, at its under side, is beveled at 12 so that it will fit the rounded bottom of the pipe bowl and in the top of its inner end portion it is formed with a plurality of air passages 13 that are preferably relatively long slots, which will freely pass the air and smoke but will intercept tobacco particles that are of such size that would be likely to clog or stop the air passage through the strainer.

The top of the central portion of the tubular strainer 10 is opened up by a long slot-forming notch 10^a. This strainer is arranged to be applied in the pipe with its slot 11 at the bottom so that not only smoke but the drippings or condensed moisture will come into direct contact with the wood of the pipe during the passage of the smoke from the bowl and so that the drippings or condensed moisture will drop into a sump or pocket 9^a formed in the stem of the pipe bowl 7 inward of that portion of the mouth piece 8 that is telescoped into said stem. Also it is important to note that when the strainer is applied, the long top notch 10^a leads from a point close to the perforations 13 into the said sump or pocket 9^a, thereby giving an extended contact of the smoke with the wood of the bowl and providing a second free passage into the sump or pocket 9^a.

These features have the effect of cooling the smoke and permitting the condensed moisture which gathers in the tube to escape

downward when it is dropped into the sump or bowl where it is trapped.

The adjustability of the split tubular stem, above described, is such that it will readily fit not only old "favored" pipes but various pipes having different bores. To make the tubular strainer further adjustable so that it will be adapted for pipes having stems of different lengths, it is formed with notches 14 at the edges of its extended end, which weakens the tube so that sections thereof may be readily broken off by bending.

It is the primary intention of this invention to provide an adjustable tubular pipe strainer that may be sold or disposed of in itself for applications of pipes already in use or for pipes having no strainers or strainers of less efficiency but it will, of course, be understood that it is my desire to cover the same whether sold independently or in connection with tobacco pipes.

In view of the resilience in the split tubular strainer, it is evident that it will snugly fit the bore of any pipe in which it is inserted but, nevertheless, it may be readily inserted or withdrawn for the purpose of cleaning the same. In actual practice, the efficiency of the improved pipe strainer has been thoroughly demonstrated.

In the preferred arrangement, the slots 13 in the inner end of the strainer tube are obliquely set, but in Fig. 7, the strainer is shown as provided with axially extended slots 13^a.

What I claim is:

- 35 1. A longitudinally split tubular pipe strainer that is longitudinally expansible and contractible to vary its diameter.
- 40 2. A longitudinally split tubular pipe strainer that is longitudinally expansible and contractible to vary its diameter, said tubular strainer, at its inner end portion, having air passages adapted to be exposed to the down-draft of the pipe in which it is applied.
- 45 3. A longitudinally split tubular pipe strainer that is longitudinally expansible and contractible to vary its diameter, said tubular strainer, at its extended end, having notches that weaken the same so that sections thereof may be broken off to vary its length.
- 50 4. A longitudinally split tubular pipe strainer that is longitudinally expansible and contractible to vary its diameter, said tubular strainer, at its inner end portion, having air passages adapted to be exposed to the down-draft of the pipe in which it is applied, said tubular strainer, at its extended end, having notches that weaken the same so that sections thereof may be broken off to vary its length.
- 55 5. A tubular pipe strainer that is adjustable both as to diameter and length so that it is adjustable to fit different pipe bores.
- 60 6. A longitudinally split tubular pipe strainer that is longitudinally expansible and contractible to vary its diameter, said tubular

strainer, at its inner end portion, having air passages adapted to be exposed to the down-draft of the pipe in which it is applied, the slit of said tube being at the normal bottom thereof and said tube in the top of its intermediate portion having a longitudinally extended notching affording an air passage.

7. The combination with a pipe bowl having a tubular stem and mouth piece, of a tubular strainer applied in said stem, and having a longitudinal slit in its bottom, and air passages in the top of its inner end portion, said tubular stem adjacent its junction with said mouth piece having a pocket or sump for condensed moisture and with which the slit in said tube communicates.

8. The combination with a pipe bowl having a tubular stem and mouth piece, of a tubular strainer applied in said stem, and having a longitudinal slit in its bottom, and air passages in the top of its inner end portion, said tubular stem adjacent its junction with said mouth piece having a pocket or sump for condensed moisture and with which the slit in said tube communicates, said tubular strainer in the top of its intermediate portion having a longitudinally extended slot affording a passage leading into said pocket or sump.

In testimony whereof I affix my signature.

HUGH M. McCLURE.
